Des. 228,699
Patented Oct. 23, 1973

228,699

PLEATED KAFTAN

George P. Keyloun, 7205 Narrows Ave.,
Brooklyn, N.Y. 11209

Filed July 2, 1970, Ser. No. 23,813

Term of patent 14 years

Int. Cl. D2—02

U.S. Cl. D2—49

FIG. 1 is a front perspective view (substantially similar to a back perspective view thereof) of the pleated kaftan, embodying the features of my new design,

FIG. 2 is an enlarged fragmentary view about the neck of the garment,

FIG. 3 is a diagrammatic layout view of the garment,

FIG. 4 is a diagrammatic layout top plan view, and

FIG. 5 is a side elevational view thereof.

I claim:

The ornamental design for a pleated kaftan, substantially as shown and described.
